CIGAR MACHINE

James P. Durning, deceased, late of St. Albans, N. Y., by Jean L. Durning, executrix, St. Albans, N. Y., assignor to International Cigar Machinery Company, a corporation of New Jersey

Original application February 17, 1944, Serial No. 522,701, now Patent No. 2,470,766, dated May 24, 1949. Divided and this application April 29, 1949, Serial No. 90,429

8 Claims. (Cl. 131—21)

1

This invention relates to cigar machines, and more particularly to improvements in cigar machines of the type wherein long filler tobacco is fed into an elongated trough formed by a bottom conveyor belt and spaced side conveying belts associated therewith which are operative to move a stream of long filler tobacco in a controlled manner to a cutter which separates predetermined lengths of tobacco from the stream of the tobacco for delivery to mechanism which forms the bunch lengths into a column from which are separated bunch charges.

This application is a division of co-pending application Serial Number 522,701, filed February 17, 1944 for Cigar Machine, now Patent No. 2,470,766, granted May 24, 1949.

In mechanisms of the type under consideration, inaccuracies may occur in the amount of tobacco advanced during each step-wise movement of the feeding conveyors so that inequalities occur in the length of tobacco forming the vertical column. The present invention constitutes a solution of this problem because it provides means for so controlling and driving the conveyors of the tobacco stream conveying system that each length of tobacco advanced thereby is satisfactorily uniform in length, and inequalities are practically eliminated.

An object of the present invention is to provide an improved conveying system for advancing long filler tobacco to a bunch length cutting mechanism and means associated therewith for so controlling the movement of the belts forming the conveyor system that at all times substantially equal lengths of tobacco will be fed and cut from said stream.

The invention further consists in the provision of improved conveyor driving mechanism and control means associated therewith which coact in such manner as to insure substantial uniform travel of the conveyor system each time the advancing end of the stream of tobacco, advanced by said conveyor system, is delivered into the range of action of a cutter which cuts off a bunch length for delivery to the bunch length assembling magazine of the cigar machine.

With these and other objects not specifically mentioned in view, the invention consists in certain constructions and combinations hereinafter fully described and set forth in the appended claims.

In the accompanying drawings, which form a part of this specification and in which like characters of reference indicate the same or like parts:

2

Figure 1 is a side elevation showing a cigar machine embodying the improved filler feed conveying and control mechanism of the invention;

5 Figure 2 is a sectional end elevation of the same taken on line 2—2 of Figure 1;

Figure 3 is a side elevation of an enlarged cigar and the drive control mechanism for the cross feed channel belts taken on line 3—3 of Figure 2;

10 Figure 4 is a similar side elevation on an enlarged scale of the feed belt control mechanism illustrating the movements of said mechanism; and

15 Figure 5 is a view showing a detail of the filler feed driving mechanism.

Referring to Figures 1 and 2, it may be noted that the stemmed leaf tobacco is placed by an operator in the filler feed channel of the cross feed, with the length of each leaf or portion of each leaf extending lengthwise of the channel to form a continuous layer or stream of tobacco of proper thickness. Said feed channel is formed by a horizontal feed belt 30 and two vertical feed belts 32 and 34. Said belts are intermittently driven from a drum 68 on a shaft 36 and pulleys 78 and 80 driven from shaft 36, the latter being supported in suitable bearings of a supporting frame 38 secured to a bed plate 40 mounted on the main frame 42 of the machine. On shaft 36 is fastened a ratchet 44 which is driven intermittently by a pair of pawls 46 (Figures 3 and 4) pivoted upon a stud 48 on the upper end of an oscillating arm 50 loosely mounted on shaft 36. Arm 50 is connected by an adjustable rod 52 to a cam lever 54 (Figure 5) carrying a cam roller 56 engaging with a cam track 58 of a cam 60 mounted on the main cam shaft 62 which is supported by suitable bearings of the main frame 42. Cam shaft 62 carries a gear (not shown) which is suitably driven from the main drive shaft of the cigar machine (not shown). Cam lever 54 is loosely mounted on a supporting shaft 66 mounted in the main frame 42.

45 The horizontal feed belt 30, which forms the bottom of the tobacco feed channel and is driven by the drum 68 secured to the intermittently rotating shaft 36, is led over several suitable idler pulleys and a guide pulley 70 (Figure 1) which is supported by an adjustable bearing to take up slack and secure the proper tension of said belt. Guide pulley 70 and its adjusting means are supported by a suitable bracket 72 attached to a member 74 which is mounted on frame 38 and supports a plate 76 (Figure 2). The plate 76 is

secured to bracket 72 and member 74 and supports the upper run of belt 30 and thereby assures a straight and even bottom on the feed channel. The inner runs of the vertical feed belts 32 and 34 form the side walls of said channel.

Belts 32 and 34, as previously mentioned, are driven by rollers 78 and 80, respectively (Figures 1 and 2). Roller 78 is secured on the upper end of a vertical shaft 82 which carries on its lower end a bevel gear 84 (Figure 2) meshing with a bevel gear 86 which is secured to the drum 68. Roller 80 is similarly mounted on a vertical shaft 88 to the lower end of which is attached a bevel gear 90 meshing with a bevel gear 92 secured to the intermittently rotating shaft 36. Each vertical belt 32 and 34 runs over one of a pair of vertical rollers 94 (Figure 1). Cover plates 96 and 98 are supported on the shafts of rollers 80, 94, and 78, 94 respectively, and the upper edges of belts 32 and 34 are guided by downwardly extending flanges on plates 96 and 98, respectively. As mentioned heretofore, the filler tobacco is placed in the filler feed channel to form a continuous layer or stream and the filler stream is advanced by the feed belts into an extension of the filler feed channel formed by two stationary side walls 100 wherein a corrugated cutter 102 severs a predetermined length from the leading end of the stream of filler tobacco. Since cutter 102 and its operating mechanism forms no specific part of the present invention, further description thereof is deemed unnecessary.

This severed section of the tobacco stream should correspond to the length of cigar bunches to be produced, and not vary during the operation of the machine. To achieve this object, the feed belt drive mechanism shown in Figures 3 and 4 is of a novel construction to eliminate all possible lost motion. In describing said drive mechanism, we may assume that one bunch length of the filler stream has been fed into the extension of the filler feed channel and oscillating arm 50 has come to rest against an adjustable stop screw 104, position I (Figure 3). Stop screw 104 is threaded into a flange of the member 74 and is adjusted to a position at which its inner end will stop the oscillating arm 50 at the end of each forward stroke thereof, thereby taking up all possible back lash.

The return stroke of arm 50 in the direction of the arrow in Figure 4, as well as its forward stroke, is produced by the action of cam lever 54 upon connecting rod 52, as previously described. Shortly after starting on their return stroke with arm 50, the pawls 46 are lifted off the ratchet 44, at the dotted position II thereof shown in Figure 4, and remain locked in this position while being carried by arm 50 to its rearmost position III shown in Figure 4. The pawls 46 are interconnected at the ends thereof which are in front of pivot 48, by a pin 106 secured in a hole in one pawl and projecting into a slightly larger hole 108 in the other pawl. To the end of pin 106 projecting from hole 108 is attached one end of a tension spring 110 (Figure 3). The other end of said spring is anchored to a stud 112 attached to arm 50. Thus the pawls 46 are held in engagement with ratchet 44 when arm 50 begins its rearward stroke. During the rearward stroke of the arm 50, the lifting of said pawls occurs when the flattened portion 114 of a pin 116, secured in the pawl in which the pin 106 is also fastened, contacts and rides upon a roller 118 which projects into the path of said flattened portion 114. Roller 118 is pivoted to a stud 119 on one end of a

double lever 120 loosely mounted on a stud 122 held in one side wall of supporting member 74. To the other end of double lever 120 is attached a tension spring 124 anchored to the same side wall of member 74. From the latter also protrudes a stop pin 125 against which the free end of double lever 120 is normally held by the tension spring 124. While pawls 46 are being lifted from ratchet 44, when flattened portion 114 of pin 116 rides over the roller 118, a projection 126 on an extension 128 of the pawl carrying pin 116, engages underneath a shoulder 130 of a latch or lock lug 132 and thereby holds the pawls in lifted position, so that said pawls do not slide upon or have any contact whatsoever with the now stationary ratchet during their return stroke with arm 50. Therefore, less wear on the teeth of the ratchet and the pawls, which can cause improper or delayed engagement during the feeding action, and a much quieter operation of the machine are obtained. Lock lug 132 is pivoted to a stud 134 on arm 50. A compression spring 136, seated in a depression in the outer end of arm 50, keeps lug 132 and projection 126 in constant engagement in either locked or unlocked position. As previously mentioned, the lifted pawls 46 are carried by arm 50 to their rearmost position III, Figure 4, where lock lug 132 contacts adjustable release screw 138, thereby compressing spring 136 and producing a slight unlatching movement of lock lug 132 which releases the projection 126 of the pawl from the shoulder 130 of lock lug 132. Thereupon the tension spring 110 pulls the pawls 46 downward toward ratchet 44, but engagement of the pawls 46 with the ratchet is prevented at this point by a stationary control cam 140 upon whose arcuate periphery 142 the flattened portion 114 of pin 116 projecting from one of the pawls 46, rides while arm 50 swings forwardly from its rearmost position, as indicated by the arrow in Figure 4. Therefore pawls 46 cannot engage with ratchet 44 and impart motion to the same until the flattened portion 114, riding on the periphery 142 of cam 140, has reached the end of said cam. Pawls 46 are then pulled downwardly by tension spring 110. It is the distance from the point where the pawls drop into engagement with ratchet 44 to the point where the arm 50 contacts the stop screw 104, which determines the amount of feed, i. e., the length of tobacco filler forwarded by the channel belts 30, 32 and 34. In order to produce uniform cigar bunches, it is of utmost importance that the length of each filler charge be uniform and even at all times. For this reason, a slot 146 is provided at the end of cam 140 and a hardened finger 144 is pivotally mounted in said slot with its arcuate tip 149 continuous with the periphery 142 of cam 140 and its outer corner 148 extending beyond the forward end of said cam, thus assuring a sharp drop when the flattened portion 114 of pin 116 rides over finger 144. To minimize lost motion due to slippage of the pawls when dropping on ratchet 44, one pawl is a distance of one-half tooth shorter than the other, giving the assurance that in any case, one of the pawls will fall immediately into engagement with a corresponding tooth of the ratchet 44. It may be noted that the provision of a sharp and solid point at the edge of the stationary cam 140, instead of the finger 144, would cause considerable damage in case lock lug 132 should fail to lock the pawls in their lifted position during their return stroke. For this reason, a compression spring 150 (Figures 3 and 4) is employed to hold finger 144 in its operative position. The latter

is normally pressed by spring 150 against a stop pin 152, but should the pawls return in an unlocked or down position, the projecting flattened portion 114 of pin 116 would simply press finger 144 out of the way and ride up on an inclined surface 154 provided for this purpose at the edge of cam 140 and slide backward on the periphery 142 of the same.

In order to provide means for changing the length of filler stream fed during each cycle, and also to permit the filler feed to be accurately set to advance the exact length of filler tobacco required for the cigar bunch, the stationary cam 140 is equipped with a scale and pivotally mounted on shaft 36. An indicator finger 156 (Figures 3 and 4) is mounted on supporting frame 38, and cam 140 may be moved to the desired position upon loosening lock screw 158 which is threaded into said cam and passes through a slot 160 in frame 38. Thus the finger 156 will designate on the scale on cam 140 the length of filler which is being fed in each cycle.

The release, and stop screw 138 (Figures 3 and 4) which trips lock lug 132 at the rearmost position of arm 50, is secured in the hub of a control member 162 loosely mounted on a stud 164 (Figures 3 and 4) held by frame 38. Member 162 is furthermore equipped with a resetter finger 166, a stop lug 168 and a lock lug 170. To the latter is attached a lock plate 172 which is held in engagement with a lock arm 174 attached to a stud 176 loosely supported by a bushing 176 held by frame 38. On the stud 178 is also secured a control arm 180 (Figures 1 and 2) to which is pivoted a control link 182. Every time link 182 moves in an upward direction, it will cause control arm 180 and lock arm 174 to move upward also, thereby effecting a disengagement of the latter from lock plate 172. The engagement of arm 174 with lock plate 172 normally holds the release and stop screw 138 in an ineffective position, as shown in Figure 3. Disengagement of arm 174 from plate 172, however, permits a tension spring 184 connecting resetter finger 166 and stud 178, to swing member 162 and bring screw 138 into the path of the oncoming lock lug 132 on arm 50. A stop pin 186, held by frame 38, engages the stop lug 168 and thereby limits the extent to which the member 162 will be displaced by spring 184. The arm 50, when reaching its rearmost position, then presses the free end of lock lug 132 against said stop screw 138 and the release of the lifted pawls 46 is effected, as previously described. After the feeding of each length of filler, the release or stop screw 138 is returned to its ineffective position by a resetter arm 188 which projects from the hub of arm 50 and oscillates with the latter. On its free end, arm 188 carries a stop screw 190 which, during the forward stroke of arms 50 and 188, engages with the free end of the resetter finger 166 and moves the same upward, thereby producing an upward movement of lock lug 170 and its plate 172. A tension spring 192 (Figures 1 and 2) connected to control arm 180, acts to maintain lock arm 174 in its downward position to re-engage the lock plate 172 when the finger 166 is disengaged by stop screw 190.

The cross feed conveyors 30, 32 and 34 are actuated during the operation of the machine whenever it is necessary to feed additional bunch lengths of tobacco to the magazine indicated generally M. The quantity of tobacco in magazine M is determined by means of a measuring plunger 352 attached to the lower end of a vertical shaft 376 suitably supported for vertical movement in

bearing brackets 378 and 380, both of which are rigidly attached to pedestal 200. Shaft 376 is reciprocated by an oscillating forked lever 382 carrying a pair of rollers 384 engaging with a collar 386 loosely mounted on shaft 376. To the latter is adjustably clamped a lug 388 against which the collar 386 is held by a compression spring 390 seated against a collar 392 fastened to shaft 376. Lever 382 is fastened on a horizontal shaft 400 supported by suitable bearings in pedestal 200. Shaft 400 carries a rocker arm 402 which is connected by an adjustable rod 404 to a suitable cam lever 406 fulcrumed on shaft 66. The downward movement of measuring plunger 352 is effected by the downward motion of lever 382 which, by means of rollers 384, depresses collar 386 and through spring 390 and collar 392, imparts downward motion to shaft 376. The tobacco column (not shown) in magazine M offers resistance to the descending measuring plunger 352, but arm 382 continues its downward stroke for a short distance, thereby compressing spring 390 and causing collar 386 to move away from lug 388. In this manner, sufficient pressure is exerted through spring 390 and collar 392 to effect compaction of the tobacco column in magazine M.

Lever 406 carries a cam follower 408 engaging with a cam track 410 of suitable design for causing the desired reciprocation of shaft 376, which cam track is formed in cam 60 mounted on shaft 62 (Figure 5).

In order to control effectively the height of the tobacco column (not shown) in magazine M, which column normally consists of several superimposed bunch lengths of tobacco, lug 388 mounted on shaft 376 carries adjustable trip screw 412 which normally during the downward movement of shaft 376 and plunger 352, engages the free end 414 of the double lever 416 pivoted to a stud 418 held by pedestal 200. The other end 420 of lever 416 is connected to feed belt link 182 (Figure 1). Therefore, when trip screw 412 engages end 414 of lever 416 and moves it downwardly, the other end 420 of lever 416 moves upwardly and through link 182 connected thereto, causes an upward movement of control arm 170 and lock arm 174. Since, as previously described, the upward movement of lock arm 174 permits stop screw 138 to move into the path of lug 132 and effect a release of lifted pawls 46, the feed belt drive control is tripped and a new charge is fed in the following cycle of the machine.

It will be noted that control arm 180 and lock arm 174 are moved downwardly by spring 192 when trip screw 412 moves away from lever 416 upon upward movement of shaft 376. This permits arm 174 to re-engage lock plate 172 when lock plate 172 is returned to its initial position by engagement of stop screw 190 with arm 166. In case the tobacco column (not shown) in magazine M is too high, that is, when too much tobacco has accumulated in magazine M, measuring plunger 352 cannot enter very far into the magazine and plunger 352 and shaft 376 come to rest before trip screw 412 can engage end 414 of lever 416. In such case, tripping of the feed belt drive control cannot take place, and control arm 180 and lock arm 174 remain in their operative positions and no release of pawls 46 is effected. Thus pawls 46 remain lifted through the following cycle and therefore the feeding action of feed belts 30, 32 and 34 is interrupted and no charge is fed during the following cycle of the machine.

The invention above described may be varied in construction within the scope of the claims, for the particular device, selected to illustrate the invention, is but one of many possible concrete embodiments of the same. It is not, therefore, to be restricted to the precise details of the structure shown and described.

What is claimed is:

1. The combination with a series of belts arranged to form a filler feed channel wherein filler tobacco may be placed to form a continuous layer, of a cutter for cutting bunch lengths from said layer, a magazine, a measuring plunger, means for cyclically moving said plunger to compress said bunch lengths in said magazine, a trip finger mounted on said plunger, means operated by said trip finger for selectively and intermittently driving said belts to advance said layer in said channel to said cutter and into said magazine, said means including a ratchet, a shaft on which said ratchet is mounted, an oscillating arm loosely mounted on said shaft, a pawl pivotally mounted on said arm and adapted to engage and drive said ratchet, a spring connected to said arm and urging said pawl toward said ratchet, a device for lifting and latching said pawl in lifted position during the rearward movement of said arm, instrumentalities operative when tobacco is to be fed to said magazine for unlatching said pawl from said device at termination of the rearward movement of said arm, a second latch controlled by said trip finger and operative to positively hold said unlatching instrumentalities out of operative position when latched, mechanism to urge said instrumentalities into operative position when they are released from said second latch, a cam having an arcuate periphery and an inwardly extending face at its forward end and adapted to support the unlatched pawl in lifted position as said arm moves forwardly whereby said pawl will drop into engagement with the ratchet as it rides over the forward end of said cam, and the pawl will drive the ratchet during the remainder of its forward movement.

2. The combination with a series of belts arranged to form a filler feed channel wherein filler tobacco may be placed to form a continuous layer, of means for intermittently driving said belts to advance said layer in said channel, said means including a ratchet, a shaft on which said ratchet is mounted, an oscillating arm loosely mounted on said shaft, a pawl pivotally mounted on said arm and adapted to engage and drive said ratchet, a spring connected to said arm and urging said pawl toward said ratchet, a device for lifting and latching said pawl in lifted position during the rearward movement of said arm, instrumentalities for unlatching said pawl from said device at termination of the rearward movement of said arm, a cam having an arcuate periphery and an inwardly extending face at its forward end and adapted to support the unlatched pawl in lifted position as said arm moves forwardly whereby said pawl will drop into engagement with the ratchet as it rides off the forward end of said cam, and the pawl will drive the ratchet during the remainder of its forward movement, an inclined surface extending between said inwardly extending face of said cam and its arcuate periphery, and a yielding finger positioned adjacent to said inwardly extending face and extending outward beyond said inclined surface and having an

arcuate periphery normally continuous with the periphery of said cam.

3. The combination with a series of belts arranged to form a filler feed channel wherein filler tobacco may be placed to form a continuous layer, of means for intermittently driving said belts to advance said layer in said channel, said means including a ratchet, a shaft on which said ratchet is mounted, an oscillating arm loosely mounted on said shaft, a pawl pivotally mounted on said arm and adapted to engage and drive said ratchet, a spring connected to said arm and urging said pawl toward said ratchet, a device for lifting and latching said pawl in lifted position during the rearward movement of said arm, instrumentalities for unlatching said pawl from said device at termination of the rearward movement of said arm, a cam having an arcuate periphery and an inwardly extending face at its forward end and adapted to support the unlatched pawl in lifted position as said arm moves forwardly whereby said pawl will drop into engagement with the ratchet as it rides over the forward end of said cam, and the pawl will drive the ratchet during the remainder of its forward movement, movable means mounting said unlatching instrumentalities proximate the position occupied by said arm at the termination of its rearward movement so that said instrumentalities may be moved into inoperative position, and a latch operative to engage said instrumentalities and hold them in inoperative position.

4. The combination with a series of belts arranged to form a filler feed channel wherein filler tobacco may be placed to form a continuous layer, of means for intermittently driving said belts to advance said layer in said channel, said means including a ratchet, a shaft on which said ratchet is mounted, an oscillating arm loosely mounted on said shaft, a pawl pivotally mounted on said arm and adapted to engage and drive said ratchet, a spring connected to said arm and urging said pawl toward said ratchet, a device for lifting and latching said pawl in lifted position during the rearward movement of said arm, instrumentalities for unlatching said pawl from said device at termination of the rearward movement of said arm, a cam having an arcuate periphery and an inwardly extending face at its forward end and adapted to support the unlatched pawl in lifted position as said arm moves forwardly whereby said pawl will drop into engagement with the ratchet as it rides over the forward end of said cam, and the pawl will drive the ratchet during the remainder of its forward movement, said instrumentalities including a pivoted member, an unlatching projection on said member, a latch surface on said member, a latch arm operative to engage said latch surface and maintain said unlatching projection in inoperative position, means operative, when said belts are to be driven to advance tobacco in said channel, for moving said latch arm out of engagement with said latch surface, and means to move said unlatching projection into position to unlatch and free said pawl for movement into operative driving relationship with said ratchet.

5. In a tobacco feeding mechanism comprising a channel formed of spaced vertical belts and a bottom tobacco supporting belt located beneath and extending between said spaced vertical belts for supporting a layer of tobacco, said mechanism including a ratchet, a shaft mounting said ratchet, an oscillating arm loosely mounted on

said shaft for travel between a foremost operative position and a rearmost inoperative position, a pawl pivotally mounted on said arm and adapted to engage and drive said ratchet, a spring urging said pawl toward said ratchet, a latch for latching said pawl in inoperative position relative to said ratchet during the movement of said arm from said foremost to said rearmost position, means located adjacent said rearmost inoperative position of said arm for unlatching said pawl whereby said spring may displace said unlatched pawl into position for actuating said ratchet, a second latch device including said pawl unlatching means, a lever, a lock arm, a linkage connecting said lever and arm, a trip finger adapted to engage said lever and move said arm to unlatch said second latch device, and means for moving said unlatching means into unlatching position relative to said first-named latch when said second latch device is unlatched.

6. In a tobacco feeding mechanism comprising a channel formed of spaced vertical belts and a bottom tobacco supporting belt located beneath and extending between said spaced vertical belts for supporting a layer of tobacco, said mechanism including a ratchet, a shaft mounting said ratchet, an oscillating arm loosely mounted on said shaft for travel between a foremost operative position and a rearmost inoperative position, a pawl pivotally mounted on said arm and adapted to engage and drive said ratchet, a spring urging said pawl toward said ratchet, a latch for latching said pawl in inoperative position relative to said ratchet during the movement of said arm from said foremost to said rearmost position, means located adjacent said rearmost inoperative position of said arm for unlatching said pawl whereby said spring may displace said unlatched pawl into position for actuating said ratchet, a second latch device retaining said pawl unlatching means in inoperative position when latched, a lever, a pivoted lock arm, a linkage connecting said lever and arm, a trip finger adapted to engage said lever and move said arm to unlatch said second latch device, a projection on said second latch device, and a projecting element on said oscillating arm positioned to engage said projection during the forward movement of said oscillating arm to reset said second latch device.

7. In a tobacco feeding mechanism comprising a channel formed of spaced vertical belts and a bottom tobacco supporting belt located beneath and extending between said spaced vertical belts for supporting a layer of tobacco, said mechanism including a ratchet, a shaft mounting said ratchet, an oscillating arm loosely mounted on said shaft for travel between a foremost operative position and a rearmost inoperative position, a pawl pivotally mounted on said arm and adapted to engage and drive said ratchet, a spring urging said pawl toward said ratchet, a latch for latching said pawl in inoperative position rela-

tive to said ratchet during the movement of said arm from said foremost to said rearmost position, means located adjacent said rearmost inoperative position of said arm for unlatching said pawl whereby said spring may displace said unlatched pawl into position for actuating said ratchet, a second latch device to hold said pawl including an unlatching means out of operative unlatching position, a lever, a pivoted arm, a link connecting said lever and arm, a trip finger, means operative when said belts are to feed tobacco for moving said trip finger to engage said lever and move said arm to unlatch said second latch device, and separate means that move said pawl unlatching member into operative unlatching position relative to said first-named latch when said second latch device is unlatched.

8. In a tobacco feeding mechanism comprising a channel formed of spaced vertical belts and a bottom tobacco supporting belt located beneath and extending between said spaced vertical belts for supporting a layer of tobacco, said mechanism including a ratchet, a shaft mounting said ratchet, an oscillating arm loosely mounted on said shaft for travel between a foremost operative position and a rearmost inoperative position, a pawl pivotally mounted on said arm and adapted to engage and drive said ratchet, a spring urging said pawl toward said ratchet, a latch for latching said pawl in inoperative position relative to said ratchet during the movement of said arm from said foremost to said rearmost position, means located adjacent said rearmost inoperative position of said arm for unlatching said pawl whereby said spring may displace said unlatched pawl into position for actuating said ratchet, a second latch device to hold said pawl unlatching means out of operative unlatching position, a lever, a pivoted arm, a link connecting said lever and arm, a trip finger, means operative when said belts are to feed tobacco for moving said trip finger to engage said lever and move said arm to unlatch said second latch device, a projecting element on said oscillating arm and a projection on said pawl unlatching means located in the path of said element during its forward movement with said oscillating arm to move said pawl unlatching means out of operative position for latching by said second latch device.
